UNITED STATES PATENT OFFICE.

CASPAR SAUER, OF ST. PAUL, MINNESOTA.

IMPROVEMENT IN HARNESS-HAMES.

Specification forming part of Letters Patent No. **156,598**, dated November 3, 1874; application filed July 18, 1874.

To all whom it may concern:

Be it known that I, CASPAR SAUER, of St. Paul, in the county of Ramsey and State of Minnesota, have invented a new and Improved Hame, of which the following is a specification:

In the accompanying drawing, Figure 1 represents a rear elevation of my improved hame; and Fig. 2, a horizontal section of the same on the line *c c*, Fig. 1.

Similar letters of reference indicate corresponding parts.

The invention will first be fully described, and then pointed out in the claim.

In the drawing, A represents the upper, B the lower, part of my improved hame. C is the connecting-sleeve, which is fitted accurately over the ends of the parts A and B, being made with segmental or other suitable cross-section. The hame parts are adjusted to any size of collar in sleeve C by means of set-screws *a*, which pass through the same, and bind firmly on the ends of the same. The

heads of set-screws *a* are preferably arranged at the rear side of the hame, to be out of sight. The rein-ring D, as well as trace-fastener E, are sliding by their sleeve-shaped parts on the hame parts A and B, and adjusted firmly thereto by set-screws *b*, being readily replaced by new ones in case of breakage without injuring thereby the whole hame.

The hame has no welded parts, and is, therefore, stronger throughout, and consequently more durable, and very convenient in use.

Having thus described my invention, I claim as new and desire to secure by Letters Patent—

A hame having the two parts A B, adjustable in a central sleeve, C, together with an adjustable rein-ring, D, and adjustable trace-fastener E, as and for the purpose described.

CASPAR SAUER.
